(57) **CLAIM**

The ornamental design for a connector for flexible printed circuit board, as shown and described.

DESCRIPTION

FIG. 1 is a bottom, front and left side perspective view of a connector for flexible printed circuit board showing our new design;

FIG. 2 is a bottom, rear and right side perspective view thereof;

FIG. 3 is a top, front and right side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is a cross-sectional view taken along the line of X—X of FIG. 4.

The broken line portion of the figure drawings is included to show unclaimed subject matter only and forms no part of the claimed design.
